UNITED STATES PATENT OFFICE.

HEINRICH AUGUST BERNTHSEN, OF MANNHEIM, AND PAUL JULIUS, OF LUDWIGSHAFEN, ASSIGNORS TO THE BADISCHE ANILIN AND SODA FABRIK, OF LUDWIGSHAFEN, GERMANY.

SUBSTANTIVE BLUE DYE.

SPECIFICATION forming part of Letters Patent No. 521,095, dated June 5, 1894.

Application filed March 30, 1894. Serial No. 505,739. (Specimens.) Patented in England February 6, 1893, No. 2,614, and in France May 15, 1893, No. 227,892.

To all whom it may concern:

Be it known that we, HEINRICH AUGUST BERNTHSEN, a subject of the King of Prussia, residing at Mannheim, in the Grand Duchy

5 of Baden, and PAUL JULIUS, a subject of the Emperor of Austria-Hungary, residing at Ludwigshafen, in the Kingdom of Bavaria, Empire of Germany, have invented new and useful Improvements in the Manufacture of new 10 Substantive Blue Dye, (for which patents have been obtained in England, No. 2,614, dated February 6, 1893, and in France, No. 227,892, dated May 15, 1893,) of which the following is a specification.

15 Our invention relates to the manufacture of a new blue dye which fixes itself on cotton goods and the like from a boiling neutral or alkaline bath without the aid of a mordant.

Our new dye is a mixed or unsymmetrical 20 disazo-dyestuff and is derived from a new amido-naphthol-sulfoacid which we have invented and which is obtained by melting with a caustic alkali the 2-4'-2' naphthylamine-disulfoacid (Armstrong and Wynne, 25 *Proceedings of the Chemical Society*, 1890, page 128) at a temperature of about 170° to 195° centigrade as more fully described in the French Patent No. 227,892, of February 13, 1893. This new acid has the constitution 30 represented by the formula:

35 40 The new dye is obtained by first preparing a so-called intermediate product by combining one molecular proportion thereof with one molecular proportion of tetrazo-ditolyl in alkaline solution and then further combining this intermediate product with one

molecular proportion of 1.4-naphthol-monosulfoacid.

Our new dye possesses a high technical value on account of its great affinity for vegetable fiber and the fastness of the colorations which it yields. These are a reddish shade of blue and resist well the action of acids and alkalies and of light. Further we have discovered that our new dye can be diazotized on the fiber by treating the goods dyed 50 with it with nitrous acid and that the resulting compound will then combine with other dyestuff-components hereinafter mentioned yielding various very fast shades of color. The components which we recommend for use in this way are for instance the naphthols, resorcinol, meta-phenylene-diamin, meta-tolylene-diamin, ethyl-beta-naphthylamin, alpha-amido-beta-naphthol-ether, para-amido-diphenylamin, and chrysoidin. 55

60 The following example will serve to illustrate the manner in which our invention can be carried into practical effect and our new dye obtained. The parts are by weight.

65 Example: Prepare a tetrazo-ditolyl-solution in the usual way from about twenty one and one fifth parts of tolidin, fifteen hundred parts of water, fifty eight parts of hydrochloric acid (containing about thirty per cent. real acid HCl) and fourteen parts of 70 sodium nitrite in ten per cent. solution. Pour this tetrazo-solution into an ice cold dilute soda solution containing about fifty parts of calcined soda and then immediately add a solution of about twenty four parts of the 75 new amido-naphthol-sulfoacid in six hundred parts of water and twenty one parts of calcined soda. When the production of the intermediate compound in the form of a brown 80 black precipitate is complete, which takes 85 but a short time, add a solution of twenty five parts of 1.4-naphthol-sulfonate of soda and stir for twelve hours or longer. Finally boil the mixture, precipitate the dye with common salt, filter, press and dry. 90

Our new dyestuff occurs as a dark powder readily soluble in both hot and cold water giving red-violent solutions, it is slightly soluble in alcohol with claret-red color, practically insoluble in benzene, ether and ligroin, it gives a beautiful blue solution in concentrated sulfuric acid and on diazotizing on the fiber the latter assumes a blue color changing on treatment with the components hereinbefore mentioned to beautiful and exceedingly fast deep shades. The new dyestuff in the form of soda salt possesses the constitution represented by the formula:

the form of soda salt possesses the constitution represented by the formula:

and which is readily soluble in hot and cold water giving red violet solutions, slightly soluble in alcohol, practically insoluble in benzene, ether and ligroin, soluble in sulfuric acid giving a beautiful blue solution and which on diazotizing on the fiber assumes a blue color, all substantially as hereinbefore described.

In testimony whereof we have hereunto set 50
our hands in the presence of two subscribing
witnesses.

HEINRICH AUGUST BERNTHSEN.
PAUL JULIUS.

Witnesses:

ERNEST F. EHRHARDT,
ADOLPH REUTLINGER.

Now what we claim as new, and desire to secure by Letters Patent, is—

As a new article of manufacture the new coloring-matter which can be derived from tetrazo-ditolyl, the 2.4'.2'-amido-naphthol-sulfoacid and 1.4-naphthol-sulfoacid and in
